US00D778197S

(12) United States Design Patent (10) Patent No.: US D778,197 S
(45) Date of Patent: * Feb. 7, 2017

(54) DIAL

(71) Applicant: SWATCH LTD, Biel/Bienne (CH)

(72) Inventor: Joana Baptista Vasconcelos,
Linda-A-Velha (PT)

(73) Assignee: SWATCH LTD, Biel/Bienne (CH)

() Term: 15 Years

(21) Appl. No.: 29/551,953

(22) Filed: Jan. 19, 2016

(30) Foreign Application Priority Data

Jul. 17, 2015 (WO) DM/087003

(51) LOC (10) Cl. 10-07

(52) U.S. Cl.

USPC D10/126

(58) Field of Classification Search

USPC D10/1-29, 30-39, 122-132

CPC A44C 25/007; A44C 25/001; A44C 21/00;
A44C 3/001; A44C 3/004
